(57) **CLAIM**

The ornamental design for an accessory for a power tool as shown and described.

DESCRIPTION

FIG. 1 is a top perspective view of an accessory for a power tool showing our new design;

FIG. 2 is a bottom perspective view of the accessory for a power tool of FIG. 1;

FIG. 3 is a top plan view of the accessory for a power tool of FIG. 1;

FIG. 4 is a bottom plan view of the accessory for a power tool of FIG. 1;

FIG. 5 is a right side elevational view of the accessory for a power tool of FIG. 1;

FIG. 6 is a left side elevational view of the accessory for a power tool of FIG. 1;

FIG. 7 is a rear elevational view of the accessory for a power tool of FIG. 1;

FIG. 8 is a front elevational view of the accessory for a power tool of FIG. 1;

FIG. 9 is a cross-sectional view of the accessory for a power tool of FIG. 1 as seen along line 9-9 of FIG. 3;

FIG. 10 is a cross-sectional view of the accessory for a power tool of FIG. 1 as seen along line 10-10 of FIG. 3; and, FIG. 11 is an enlarged cross-sectional view of a portion of the accessory for a power tool of FIG. 1, where the portion corresponds to the area of FIG. 10 encircled by a dot-dashed line and referenced by number 11.

The broken lines in the drawings illustrate portions of the accessory for a power tool that form no part of the claimed design.

1 Claim, 4 Drawing Sheets
